UNITED STATES PATENT OFFICE.

SYLVANUS HUSSEY, OF SILVER CREEK, NEW YORK.

ROCK-DRILL.

SPECIFICATION forming part of Letters Patent No. 330,489, dated November 17, 1885.

Application filed January 29, 1884. Serial No. 119,112. (No model.)

To all whom it may concern:

Be it known that I, SYLVANUS HUSSEY, of Silver Creek, in the county of Chautauqua and State of New York, have invented new 5 and useful Improvements in Rock-Drills, of which the following is a specification.

This invention relates more particularly to that class of rock-drills which are operated by hand, and has for its object to improve the 10 actuating mechanism whereby the drill-bar is raised, the spring mechanism whereby the blow is delivered, and the clutch-head which seizes the drill-bar.

My invention consists to these ends in the 15 improvements in the construction of the drill, which will be hereinafter fully set forth, and pointed out in the claims.

In the accompanying drawings, consisting of two sheets, Figure 1 is a front elevation of 20 my improved drill. Fig. 2 is a fragmentary side elevation partly in section. Fig. 3 is a top plan view of the mechanism whereby the drill-bar is raised. Fig. 4 is a vertical section of the geared parts of the actuating mechanism. Fig. 5 is a sectional elevation of the 25 clutch-head on an enlarged scale. Figs. 6 and 7 are horizontal sections in lines $x\ x$ and $y\ y$, Fig. 5, respectively. Fig. 8 is a top plan view of the lower seat-ring of the clamping-jaws. Fig. 9 is a sectional elevation of the upper 30 seat-ring. Fig. 10 is a fragmentary sectional elevation of a modified construction of the clutch-head. Fig. 11 is a fragmentary sectional elevation on an enlarged scale of one of 35 the springs and connecting parts at right angles to Fig. 1.

Like letters of reference refer to like parts in the several figures.

A represents the tripod-base, and A' the 40 main frame pivoted to the base in any well-known or suitable manner.

A² represents the swinging frame, hung up on the horizontal shaft a , and made adjustable thereon by means of arms a' and segments a'' 45 in a well-known manner. The shaft a is supported in bearings in the frame A'.

b represents the counter-shaft, supported in bearings secured to the swinging frame A², and b' b² are the gear-wheels secured, respectively, 50 to the shafts a and b , whereby motion is transmitted to the shaft b from the shaft a , the latter being provided with hand-cranks a^3 .

C represents the actuating gear-segment, secured to the counter-shaft b , the two similar parts of the segment being arranged on opposite sides of the shaft with sufficient intervening spaces to permit the release of the actuating-lever D, whereby the drill-bar d is raised, and which is loosely mounted on the driving-shaft a . 55

E represents a gear-segment formed on the rear end of the lever D, and adapted to mesh with each part of the segment C, so that the rotation of the shaft b will alternately depress the rear end of the lever D and release the 60 same. 65

e e represent rollers attached to the lower end of the segment E, on both sides thereof, and f f are projecting arms or horns secured to the front end of each part of the segment 70 C, on each side thereof, and adapted to engage against the rollers e before the teeth of the respective segments mesh, thereby setting the lever D in motion and placing it in the proper position to cause an easy and regular engagement and movement of the teeth of the 75 respective segments. The arms f are made stronger than the teeth, thereby enabling the arms to better withstand the shocks to which they are subjected in starting the lever D and 80 relieving the teeth from these shocks, the teeth being subjected only to the regular and easy motion of gear-wheels. The rollers e render the engagement and disengagement of the arms f and the lever D easy. 85

f' f' represent rollers attached to the segment C, at the rear end of each toothed portion thereof, and adapted to engage against the rear side of the last tooth e', of the segment E, thereby rendering the disengagement of the 90 segments easy. The last tooth e', of the segment E is made of steel or other strong metal, and secured to the segment by screws or bolts, so that it can be renewed when broken. The revolving segment C is by this mechanism intermittently geared with the segment E without creating considerable friction, and the power is transmitted from the shaft b to the 95 lever D in a steady and uniform manner, as the relative leverage of the actuating-segment C and lever D remains substantially the same while these parts remain in engagement. 100

G represents the clutch-head or gripping mechanism, through which the drill-bar passes,

and which seizes the drill-bar both during its upward and downward movement. The lever D is provided with an elongated opening, d' , through which the drill-bar passes.

5 g is a convex bearing-piece, which surrounds the opening d' on the upper side of the lever D, and which bears against the lower end of a sleeve, g' , which depends from the clutch-head and surrounds the drill-bar.

10 h represents connecting-rods, pivoted with their lower ends to the lever D, nearer the shaft a than the point at which the piece g bears against the sleeve g' , so that the portion of the lever D which actuates the sleeve g'

15 moves through a longer arc than the portion which actuates the rods h . The upper ends of the rods h are provided with adjustable heads h' , which connect with the upper portion of the clutch mechanism.

20 I represents the central portion of the casing of the clutch or gripping mechanism, and J the gripping-jaws, which surround the drill-bar d . The jaws J, preferably three in number, are provided on their inner sides with

25 clamping-surfaces j , and on their outer sides or backs with ribs or projections j' , which are seated loosely in recesses formed in the casing I, and extend straight across the jaws, whereby each jaw is held in place and prevented

30 from turning with the drill-bar. The upper portion of each seat for a rib, j' , is formed in the portion I of the casing, as shown at j^2 , and the lower portion of each seat is formed in a ring, I' , as shown at j^3 in Figs. 5 and 8. The

35 ring I' is held in place by the lower portion, I^2 , of the casing. The ribs j' may be made square on their lower sides, as represented in Fig. 10. The jaws J are provided with downwardly-extending arms K and upwardly-ex-

40 tending arms K' . The lower portions of the lower arms, K, are turned out conically on their inner sides to fit around the spreading-cone L, which is secured to the upper end of the sleeve g' , and rests by a flange, l , upon the

45 lower head, I^3 , of the casing. M represents a movable head arranged in the upper portion of the casing, and provided with an upwardly-tapering recess, m , which fits over the ends of the upper arms, K' . The

50 head M is provided with an annular shoulder, m' , which engages under an inwardly-turned

annular flange, m^2 , formed on the upper portion, I^4 , of the casing. n represents two laterally-projecting studs secured to the head M,

55 and engaging in elongated holes formed in the heads h' at the upper ends of the connecting-rods h .

o represents a sleeve surrounding the drill-bar and resting upon the head M.

60 o' is a cross-head formed on or secured to the upper end of the sleeve o , and provided with two lugs, o^2 , to which are pivoted two outwardly-extending links, o^3 . The outer ends of the links o^3 are pivoted to the outer ends

65 of links o^4 , which latter are pivoted at their inner ends to lugs o^5 , secured to a cross-piece, P, of the swinging frame A².

q are spiral springs coiled around two upright tubular cores or supports, q' , arranged on opposite sides of the drill-bar and secured 70 with their lower ends to brackets q^2 , which are attached to the side pieces of the frame A².

r represents rods extending downwardly from the links o^4 into the tubes q' , and provided at their lower ends with cross-pieces r' , 75 which project outwardly through vertical slots r^2 in the tubes q' . The lower ends of the springs q rest upon rings or washers r^3 , which latter rest in turn upon the cross-pieces r' .

The upper ends of the springs q bear against 80 screw-nuts r^4 , which are applied to the externally-screw-threaded upper ends of the tubes q' . By raising and lowering the nuts r^4 the tension of the springs is regulated in such manner that the springs are not entirely released when the drill-bar rests upon the rock, thereby keeping the drill-bar under sufficient pressure at the end of its downward stroke to prevent it from rebounding. This arrangement of the springs permits the employment 85

of long springs without increasing the height of the machine, and reduces the compressing movement of the springs, thereby preventing the rapid wear of the springs. When the drill-bar rests upon the rock, the parts are in the 90

position represented in Fig. 2, with the bearing-piece g slightly below the sleeve g' , the latter being adjusted by the screw-thread at its upper end to assume this position when the spreading-cone rests upon the lower head, I^3 , 95

of the clutch-casing. As the front end of the lever D moves upwardly, the rods h first lift the upper head, M, and disengage it from the upper arms, K' , of the clamping-jaws J. The head M next lifts the clutch-casing by the 100

shoulder m' engaging under the flange m^2 , thereby raising the released clamping-jaws J on the drill-bar. The bearing-piece g , traveling with greater speed than the rods h , next comes 105

in contact with the lower end of the sleeve g' and raises the latter and the spreading-cone L, thereby spreading the lower arms, K, of 110

the jaws J and tightening the latter on the drill-bar. The distance through which the jaws J are raised in this manner on the drill-bar before they are tightened constitutes 115

the feed. During the remainder of the upward movement of the lever D the sleeve g' rises faster than the rods h and the upper head, M, is retarded by the pressure of the 120

springs, and comes in contact with the upper arms, K' , the studs n rising in the slots of the upper heads, h' . The sleeve o rises with the head M, thereby raising the rods r and compressing the springs q . This continues 125

until the actuating-segment C clears the segment E of the lever D, when the rod d is forced down by the reaction of the springs. At the end of the downward movement the spreading-head L drops away from the lower arms, 130

K, and the parts are again in position for the next upward movement.

I do not intend to claim in this application the improvements in the clutch-head which

are claimed in my prior application, filed January 25, 1883, No. 83,031, nor the improvements in the actuating mechanism, clutch-head, and feed mechanism claimed in my 5 pending application No. 148,883, filed November 26, 1884.

I claim as my invention—

1. The combination, with the drill-bar and clutch mechanism, of the lifting-lever D, having 10 a gear-segment, E, provided with starting-rollers e, and an actuating gear-segment, C, having starting-arms f, substantially as set forth.

2. The combination, with the drill-bar and 15 clutch mechanism, of the lifting-lever D, having a gear-segment, E, and an actuating gear-segment, C, having a releasing-roller, f', substantially as set forth.

3. The combination, with the drill-bar and 20 clutch-head, of the lifting-lever D, having a gear-segment, E, provided with starting-rollers e, and an actuating gear-segment, C, having starting-arms f, and a releasing-roller, f', substantially as set forth.

25 4. The combination, with the drill-bar and clutch-head, of an actuating gear-segment, C, and a lifting-lever, D, having a gear-segment, E, provided with a detachable rear tooth, e', substantially as set forth.

30 5. The combination, with the drill-bar, drill-frame, and clutch-head, of the links o³, pivoted to the clutch-head, the links o⁴, pivoted to the drill-frame and the links o³, the rods r, attached to the links o⁴, and the springs 35 q, applied to the rods r, substantially as set forth.

6. The combination, with the drill-bar, drill-frame, and clutch-head, of the links o³, pivoted to the clutch-head, the links o⁴, piv-

oted to the drill-frame and the links o³, tubular supports q', secured to the drill-frame, and provided with slots r², rods r, attached to the links o⁴, and provided within the supports q' with projections r', and springs q, substantially as set forth. 40

7. The combination, with the drill-bar, drill-frame, and the clutch-head having an upper movable head, M, of the sleeve o, resting on the head M, links o³, pivoted to the sleeve o, links o⁴, pivoted to the drill-frame and 45 the links o³, tubular supports q', rods r, attached to the links o⁴, springs q, and screw-nuts r⁴, substantially as set forth.

8. The combination, with the clutch-casing, of the clamping-jaws J, pivoted to said casing, an upper head, M, adapted to tighten the jaws by its downward movement and to raise the casing by its upward movement, a cone, L, adapted to tighten the jaws by its upward movement, and a single actuating-lever 60 connected with the upper head, M, by slotted rods h and the lower cone, L, by a sleeve, g', whose point of contact with the actuating-lever is farther from the fulcrum of said lever than the point at which the rods h are attached 65 thereto, to raise the upper head, the casing, and jaws in advance of the cone at the beginning of the upward stroke, to give the feed and to cause the cone to tighten the jaws on the drill-bar after the feed has been given, substantially as set forth. 70

Witness my hand this 21st day of January, 1884.

SYLVANUS HUSSEY.
